United States Patent Office

Des. 178,832
Patented Sept. 25, 1956

178,832

CHRISTMAS TREE ORNAMENT

Astrid S. Giorklint, Los Angeles, Calif.

Application December 27, 1954, Serial No. 33,689

Term of patent 14 years

(Cl. D29—1)

FIG. 1.

FIG. 2.

FIG. 3.

FIG. 4.

Fig. 1 is an elevational view of the Christmas tree ornament as seen from either the front or back thereof showing my new design;

Fig. 2 is a side view thereof;

Fig. 3 is a perspective view; and

Fig. 4 is a plan view.

I claim:

The ornamental design for a Christmas tree ornament, as shown.
